Attorney

UNITED STATES PATENT OFFICE.

CLAUDE S. BUCHANAN, OF DAYTON, OHIO.

FILING DEVICE.

Application filed June 27, 1923. Serial No. 648,052.

To all whom it may concern:

Be it known that I, CLAUDE S. BUCHANAN, a citizen of the United States, residing at Dayton, in the county of Montgomery and State of Ohio, have invented certain new and useful Improvements in Filling Devices, of which the following is a specification.

This invention relates in general to filing devices and more particularly to a device for filing cards or inserts in such a manner that they shall be visible and that the cards shall be easily re-arranged or re-classified.

It is a purpose of my invention to provide filing devices which shall be composed of a minimum of exceedingly simple parts, the major portion thereof being readily stamped or shaped out of sheet material.

It is the further purpose of my devices to provide for the insertion or re-arrangement of said cards or inserts with a minimum of re-arrangement of the remaining cards or inserts. A complete description of my invention will be found in the accompanying drawings and specifications, in which:

Fig. 1 is a front elevation of my device assembled ready for use, while;

Fig. 1^a shows sections of a disassembly of parts of the device given in the figure above.

Fig. 2 is an enlarged front elevation of the central insert retainer, with portions broken away to show a portion of the back plate, while;

Figure 2^a is a section taken on line 2—2^a of Figure 2;

Figure 3 is a section taken on line 3—3 Figure 1.

Referring to the details in the above figures, 1 is the back plate made preferably of sheet metal. At the inner portion of this sheet metal back plate, the plate has been formed upwards into two retaining grooves, noted as 2 and 2, Fig. 1^a. The junction between the two grooves forms an "inverted U", slightly exceeding in height above the top surface of the back plate, the thickness of the inserts 6 and 7. At the lateral outer portions of the sheet metal back plate, the plate has been crimped over to form retaining guide-way flanges 3 and 4. These two guide-way flanges 3 and 4 are also slightly in excess, in inner U dimension, of the thickness of inserts 6 and 7, Fig. 1^a. The purpose of having these measurements slightly exceed the thickness of the inserts 6 and 7 will be hereinafter described.

Mounted along the center line of the "inverted U", hereinbefore described, is a detachable front plate or central insert retainer 5, shown in Figs. 1, 1^a, 2 and 2^a respectively. Same, composed preferably of sheet metal, is exceedingly simple, being formed of a single metal strip pierced by one or more rivet holes. Recessed rivets 14 are permanently secured to the central insert retainer as shown in Fig. 1^a. Corresponding retainer rivet holes 15 are provided immediately beneath each retaining rivet 14, in the "inverted U" section of the sheet metal back plate 1. Fig. 2 shows an enlarged plan view of retaining rivet hole 15. Same has been formed in such a manner as to receive and retain the recessed portion and head of retaining rivet 14, upon side-wise movement after insertion, as shown in Figs. 2 and 2^a. The purpose of securely holding the central insert retainer 5, against the "inverted U" portion of the sheet metal back plate 1 will be hereinafter described.

As shown in Figs. 1 and 3, lower insert retainers 8 and 9 have been provided at the lower portion of sheet metal back plate 1. Same have been secured by crimping the sheet metal in such a manner that shoulders (8 and 9) have been provided for the retention of the lowest inserts (of 6 and 7) of the entire group of inserts, as shown in Figs. 1 and 3.

As shown in Fig. 1, hanging up holes 10 and 11 have been provided at the upper portion of the sheet metal back plate 1. Same have been provided as a means of retaining the entire filing device in a vertical or semi-vertical position during all periods of reference.

In Fig. 1, typical cards or inserts 6 and 7 are shown in position. Title cards or inserts 12 and 13 have been so placed as to indicate the text of the subject matter immediately below. The central insert retainer may or may not have guide lines or markings connecting or relating to the subject matter of the two columns.

From the foregoing my device may be seen to operate as follows: The cards or inserts are maintained as shown in relative positions on the sheet metal back plate 1, resting upon the lower insert retainers 8 and 9 of the back plate 1, and prevented from lateral movement and held from forward movement by the central insert retainer 5 and the guide-way flanges 3 and 4 of the back plate 1, Figs.

1 and 1^a. The guide-way flanges 3 and 4, as well as the inner retaining grooves formed by the junction of 5 and the "inverted U" of the back plate 1, are so constructed as to permit of the free vertical movement of the cards or inserts 6 and 7. When it is desired to change the relative position of any of the cards or inserts, the filing device is removed from its vertical or semi-vertical reference position and placed sufficiently in a horizontal position to permit of rearrangement. The desired change is then effected by creating rearrangement through the movement of one or more inserts vertically to any desired position or having previously removed the central insert retainer 5, by creating insert vacancy thru lateral removal of one or more inserts. In case of the former rearrangement, title inserts, together with any surplus subject inserts, are permitted to slip entirely without the guide way flanges 3 and 4 of the filing device. New or previously removed inserts are then introduced laterally into the vacancies heretofore obtained (by vertical or lateral removal). The central insert retainer is then replaced and the entire filing device returned to its reference position. Title inserts should preferably be inserted at the head of subject matter.

30 Thus I have provided a filing device of exceedingly simple operation and design which can be cheaply and easily manufactured and operated, and which will provide for the insertion of a card or insert at any given position without the removal of and with the minimum disarrangement of any of the remaining inserts.

I claim:

40 1. A filing device comprising in combination; a back plate of sheet metal material, the lateral portion of whose edges are crimped to form retaining flanges and a center portion of whose surface is substantially raised in a spaced inverted U-shape, said flanges and said raised portion being adapt-

45

ed to form longitudinal guideways; and a front plate centrally and longitudinally mounted upon the raised portion of the back plate, said front plate being greater in width than said raised portion of the back plate. 50

2. A filing device comprising in combination; a back plate of sheet metal material, the lateral portion of whose edges are crimped to form retaining flanges and a center portion of whose surface is substantially 55 raised in a spaced inverted U-shape, said flanges and said raised portion being adapted to form longitudinal guideways; a front plate centrally and longitudinally mounted upon the raised portion of the back plate, 60 said front plate being greater in width than said raised portion of the back plate; and means for longitudinally securing said front plate to said back plate, said securing means comprising a plurality of recessed rivets permanently 65 secured to said front plate and provided with correspondingly slotted holes in the raised portion of the back plate.

3. A filing device comprising in combination; a back plate of sheet metal material, 70 the lateral portion of whose edges are crimped to form retaining flanges, a center portion of whose surface is substantially raised in a spaced inverted U-shape, said flanges and said raised portion being adapted 75 to form longitudinal guideways, and the lower portion of whose surface is crimped into two shoulders; a front plate centrally and longitudinally mounted upon the raised portion of the back plate, said front plate being greater in width than said raised portion of the back plate; and means for longitudinally securing said front plate to said back plate, said securing means comprising a plurality of recessed rivets permanently 80 secured to said front plate and provided with correspondingly slotted holes in the raised portion of the back plate. 85

In testimony whereof I affix my signature.

CLAUDE S. BUCHANAN.
